UNITED STATES PATENT OFFICE

2,594,043

SELECTIVE SWITCHING SYSTEM

Arie Liberman, Chicago, Ill.

Application November 9, 1949, Serial No. 126,327

2 Claims. (Cl. 177—353)

1

This invention relates to a switching system, and more particularly to a switching system having primary switch means and secondary switch means for selecting certain terminals of the primary switch means.

An important feature of this invention is that it provides an improved system enabling a standardized cabinet and set of switches to be used for intercommunication systems of greatly differing numbers of stations; another feature of this invention is that it provides primary switch means having a plurality of simultaneously operable terminals and secondary switch means for selecting certain of said plurality of terminals, only the selected terminals being activated in accordance with the position of the secondary switch means; a further feature of the invention is that the primary switch means comprise at least one group of single-throw switches, the switches in each group having a common operating means; yet another feature of the invention is that the secondary switch means comprise at least one double-throw switch having a movable pole and a pair of stationary contacts, said stationary contacts being connected to the terminals of the primary switch means for activating only selected terminals in accordance with the position of said movable pole; still a further feature of the invention is that tertiary switch means may be connected to the secondary switch means, only a portion of the primary switch means being activated in accordance with the position of the secondary and tertiary switch means; an additional feature of the invention is that it provides a switching system particularly adapted for use in an intercommunication system wherein a large number of stations may be provided while utilizing a much smaller number of manual switching means; and yet a further feature of the invention is that it provides a switching system which may be used in intercommunication systems having a wide variation in the number and/or arrangement of stations employed while utilizing the same number of manual switch means regardless of the number and/or arrangement of stations employed.

Other features and advantages of the invention will be apparent from the following specification taken in connection with the accompanying drawings, in which:

Fig. 1 is a front elevational view of an intercommunication station utilizing the invention;

Fig. 2 is an end elevational view of the apparatus of Fig. 1; and

Figs. 3A and 3B together comprise a schematic

2

wiring diagram showing the improved switching system.

An intercommunication system of the character illustrating an embodiment of this invention comprises a plurality of stations connected to each other to provide intercommunication. The term "local station" is herein employed merely to designate the particular station the operation of which is being disclosed, and the term "distant station" is herein employed merely to designate other stations in the system, without regard to the actual location of these other stations. The stations may be so-called "master stations" including an amplifier, or may be so-called "staff stations" which have no amplifier, but merely comprise a translating device (as a speaker-microphone) and switching means. A master station may communicate with a staff station or another master station, the voice of the operator of the master station being amplified at his local station and then being connected to a desired distant station through a switching system as will be herein disclosed. However, a staff station has no amplifier and generally may communicate (or at least originate a conversation) only with master stations (normally few in number) to which the staff station is connected, the amplifier in the master station being utilized to render audible the signal which originates at the staff station.

In certain intercommunicating systems means are provided wherein certain stations may be "private"—i. e., a station may be connected or arranged in such manner that sounds at that location can be heard only after that person moves his "talk-listen" switch to "talk" position. Other stations in the same system may be so arranged, if desired, that they are "non-private"—i. e., any master station making connection to that station through operating the appropriate connector switch may hear anything at that non-private location without any act by the person there.

In manufacturing intercommunication systems, it is highly desirable to standardize the electrical and mechanical equipment utilized despite the fact that there are many different arrangements in which the stations may be used, and the number of stations used in any given system may vary from only a few stations, as a half dozen, to a large number, as thirty or forty stations. It is, of course, undesirable to provide a different cabinet, a different mechanical arrangement of parts and a different number of switching devices for each unit manufactured,

and it would be impossible efficiently to manufacture intercommunication systems if it were necessary to provide a different type of cabinet and mechanical switching arrangement for each intercommunication system having different numbers of stations or different arrangements between the stations in the system.

I have devised and am here disclosing and claiming a switching system which makes it possible to use a standardized cabinet for master stations which is small and of modern design and which is suitable for any arrangement desired by the purchaser of the intercommunication system, regardless of the number of stations in the system, at least up to any reasonable limit. Furthermore, as a principal feature of the invention the same number of manually operated switch devices for connecting in different distant stations are provided and utilized regardless of the number of stations in the system, and there may be many more stations in the system than there are manual switch arrangements. The cabinet used in Fig. 1 may be utilized in a six, ten or twelve station arrangement, for example; or the same cabinet with the same switching means may be utilized in a forty station arrangement as illustrated in Fig. 3. Similarly, any lesser number of stations (as twenty or thirty) may be connected in as desired and the same cabinet may be used, thus making it possible to standardize the manufacture and to provide a small cabinet of modern design using the same parts regardless of the number of stations in the system.

The basic principle of my improved arrangement is that it provides primary switch means having a plurality of simultaneously operable terminals and secondary switch means for selecting certain of said plurality of terminals together with connections between the primary and secondary switch means for activating only the selected terminals to connect the local station with a selected distant station in accordance with the position of the secondary switch means.

Referring to the drawings, Fig. 1 shows a master station cabinet, it being understood that this station is connected to a plurality of distant stations some of which may be master stations and some of which may be staff stations in the normal installation. The station shown in Fig. 1 is designated a local station merely because it is the station the operation of which will be described. The station comprises a cabinet 10 housing an amplifier, speaker and microphone, and switching arrangement. On the face of the cabinet is a control knob 11 which may be a combination on-off switch and volume control knob, as is well understood in the art. A switch bar 12 operates a "talk-listen" switch more fully disclosed in Fig. 3, and across the face of the cabinet is a row of twelve push buttons 13, 14, 15, 16, 17, 18, 19, 20, 21, 22, 23 and 24. These push buttons operate the station selector switches and while illustrated as push button switches, obviously other types of switches, as rotary selector switches for example, can be utilized. Inasmuch as the station shown is assumed to be a part of a forty station system, there are forty stations controlled by the twelve push buttons on the panel. As shown in Fig. 1, the first push button identified as 13 is pushed in to connect the local station to any one of four distant stations numbered 1, 11, 21 and 31, as determined by the selector system hereinafter described, each station in the system being assigned a number for convenience. Similarly, the second push button may be utilized to connect

with either of stations 2, 12, 22 or 32, and each of the remaining push buttons 15, 16, 17, 18, 19, 20, 21 and 22 (i. e., the first ten in all) may be utilized to connect the local station with any one of four distant stations as noted on the face of each push button. Of course, the local station being described itself utilizes one station number and is a part of the 40 station system.

Push button 23 may be best explained as an "add 10" switch. For example, when push button 16 alone is pushed the local station illustrated will be connected to distant station No. 4. When it is desired to connect the local station to distant station No. 14 push buttons 16 and 23 are both pushed, these connections being explained in the disclosure of Fig. 3.

Push button 24 may be considered as an "add 20" switch, and pushing buttons 16 and 24 will connect the local station with station 24. As disclosed later in connection with Fig. 3, pushing in one of the station push buttons together with both push buttons 23 and 24 will "add 30." For example, if push buttons 16, 23 and 24 are all pushed, the local station will be connected with distant station No. 34.

I am able, therefore, to connect the local station shown in Fig. 1 with any one of thirty-nine distant stations, while at the same time providing only twelve push button switches for the operator of the local station. In the event the purchaser of the intercommunication system did not want forty stations but wanted a lesser number as, for example, ten stations or twenty stations or thirty stations, the same cabinet provided with the same push buttons 13-24 could be used. In this event each push button would only designate the stations which it is utilized with, and I provide paper tabs having the various station numbers thereon to cover a situation where a different number of stations are in the system. If fewer stations are used, as twenty stations or less, one of the push buttons, as 24, may be utilized solely to provide "paging" as is well understood in the art; or even with a larger number of stations in the system it may provide paging when none of the station buttons is actuated.

Furthermore, as the description of Fig. 3 proceeds, it will be obvious that the same cabinet and push button arrangement of Fig. 1 can be utilized if desired to provide for 50, 60 or any higher number of stations merely by adding contacts to the switches shown in Fig. 3.

Referring now to Fig. 3, the talk-listen switch 12 comprises a ganged combination of switches including six single pole double-throw switches 30, 31, 32, 33, 34 and 35, and two single pole single-throw switches 36 and 37, all the switches 30-37 being operated simultaneously by a single control. The push button 13 comprises a single control for simultaneously operating four double-pole single-throw switches 40, 41, 42 and 43; the push button 14 acts as a single control for four double-pole single-throw switches 44 to 47; and similarly, push buttons 15, 16, 17, 18 and 19 each provide a common operating means for a group of four double-pole single-throw switches which are not shown in Fig. 3 in order to simplify the drawing. The push button 20 is shown as comprising a common operating means for a group of four double-pole single-throw switches 50, 51, 52 and 53; push button 21 as comprising a common operating means for a group of four double-pole single-throw switches 55, 56, 57 and 58; and push button 22 as comprising a common operating means for another group of four double-pole

single-throw switches 60, 61, 62 and 63. As noted earlier all the switches may, if desired, be of some other type, as rotary selector switches.

Push button 23 provides a common operating means for four double-pole double-throw switches 65, 66, 67 and 68; and push button 24 comprises a common operating means for two double-pole double-throw switches 70 and 71. An amplifier 75 is also within the cabinet 10, this amplifier (illustrated in block form since it may be of conventional design) having a pair of input leads 76 and 77 and a pair of output leads 78 and 79. A conventional combination speaker-microphone 80 is also in the cabinet 10.

The talk-listen switching arrangement comprising the ganged switches 30-37 is illustrated as being in "talk" position. This is the position which would be assumed if the touch bar 12 of Fig. 1 were pushed down, and when the touch bar 12 is released it assumes the position shown in Fig. 1, which throws the switches 30-37 to the position other than that shown in the drawings.

Each of the single-throw switches associated with the push button 13-22 has a pair of upper terminals (as the parts are positioned in the drawings) for connection to the local station with which the switches are associated, and each switch has a pair of lower terminals for connection to a distant station. For example, the lower switch 40 would be connected to distant station No. 1; the lower terminals of switch 41 would be connected to distant station No. 11; the lower terminals of switch 42 would be connected to distant station No. 21; and the lower terminals of switch 43 would be connected to distant station No. 31. All of these connections are illustrated as conventional two-wire connections which may be completed through a junction box and cable.

While any desired arrangement of "private" and "non-private" stations may be made, as is more fully described in my copending application Serial No. 129,411, filed November 25, 1949, it is assumed that the stations controlled by push buttons 13 and 14 are connected for private operation and the stations controlled by buttons 20, 21 and 22 are connected for non-private operation. All of the switches associated with the push buttons 13-22 are connected to the local station through the switches associated with the push buttons 23 and 24, push button 23 being operated when it is desired to add ten to the number of the station normally controlled by any of the push buttons 13-22; push button 24 being operated when it is desired to add 20; and both push buttons 23 and 24 being operated when it is desired to add 30 to the number of the station normally controlled by any one of the push buttons 13-22.

Referring to the push button 23, the switch 65 is utilized to add ten in affecting those stations connected for private conversation; the switch 66 is utilized to add ten affecting those stations connected for non-private conversation; the switch 67 is utilized when twenty or thirty are added affecting those stations connected for private conversation; and the switch 68 is utilized when twenty or thirty are added affecting those stations connected for non-private conversation.

Referring to the push button 24, the switch 70 is utilized for adding twenty or thirty affecting those stations connected for private conversation; and the switch 71 is utilized for adding twenty or thirty affecting those stations connected for non-private conversations.

As noted earlier, the station is shown with the

talk-listen switch in talk position. If the operator of the local station wishes to talk to distant station No. 2 (it being assumed, of course, that the amplifier is supplied with proper operating voltages from a power pack connected to a source of voltage, as for example, to a commercial 110 volt system) the operator merely pushes push button 14, thus closing switches 44, 45, 46 and 47. However, the local station is connected only with one of these distant stations—station 2 as the parts are shown. This connection may be traced as follows: a lead 81 connects the microphone with the movable pole of the switch 30, which, in talk position, engages the left contact of said switch, 15 this left contact being connected by a lead 82 to the input lead 76 of the amplifier. Another lead 83 connects the microphone with the movable pole of switch 32 which engages the left stationary contact of this switch, and this stationary contact 20 is connected by a lead 84 with the amplifier input lead 77. The voice of the operator is amplified in the amplifier 77 and the voice signal appears across leads 78 and 79 which respectively connect with the movable pole of switches 34 and 35. The 25 closed stationary contact of switch 34 connects with a common lead 85 and the closed stationary contact of the switch 35 connects with a complementary common lead 86, these being the common leads of the "private" type of connection. The 30 leads 85 and 86 connect with the movable poles of switch 70. The two upper stationary contacts of switch 70 are connected by means of respective leads 87 and 88 to the movable poles of switch 65; and the upper stationary contacts of switch 35 35 65 are connected by means of leads 89 and 90 to the upper contacts of one of the switches in each group of switches which are operated by station selecting push buttons 13-22 and which are connected for private conversation. In Fig. 3A the 40 leads 89 and 90 are shown as connecting with the upper terminals of switches 40 and 44. However, switch 40 is open so distant station No. 1 is unaffected. Switch 44 (as well as switches 45, 46 and 47) is assumed to be closed so that the 45 circuit is complete through the switch 44 to distant station No. 2. None of the other switches 45, 46 or 47 are affected despite the fact that these switches are closed since none of these switches are connected to the local station with the parts 50 in the position shown.

If instead of station No. 2, the operator wishes to talk to station No. 12, in addition to closing push button 14, the operator would have closed push button 23, thus moving switches 65, 66, 67 and 68 from the position shown to the other position wherein the movable poles of these switches close with the lower contacts of the switches. Now with the parts in this position, the leads 87 and 88 would no longer connect with the leads 89 and 90, and the switches 40 and 44 would be disconnected from the local station. However, the lower stationary contacts of the switch 65 are connected by respective leads 91 and 92 to the upper contacts of another switch in each group of station selector switches, here shown as switch 41 in the group operated by push button 13 and as switch 45 in the group operated by push button 14. With switch 65 moved to the position other than that illustrated, the local station would be connected with distant station No. 12, leads from the lower terminals of switch 45 making this connection with distant station No. 12.

On the other hand, assuming the operator wishes to talk to distant station No. 22, he would,

of course, operate push button 14 as before, but instead of operating push button 23 he would leave the switches associated with this push button in the position shown in Fig. 3 and would instead operate push button 24 moving the switches 70 and 71 to the position other than that shown in the drawing so that the movable poles of these switches close with the lower contacts thereof. This action would disconnect the leads 87 and 88 at the switch 70 and would connect the leads 85 and 86 to leads 93 and 94 which connect with the respective movable poles of switch 67. With this switch in the position as shown in Fig. 3, another one of the switches in each group of "private" selector switches is connected to the local station. Leads 95 and 96 connect the upper contacts of switch 67 with the upper terminals of switches 42 and 46, so that the local station would be connected in the illustration given, to station 22 through switch 46.

In the event the operator wishes to talk to distant station No. 32 he would operate push buttons 14, 23 and 24. The circuit would be the same as just above described down through leads 93 and 94. However, now the movable poles of switch 67 closes the lower contacts of said switch, and these contacts are connected by leads 97 and 98 to the fourth switch of each group of private stations, here shown as switches 43 and 47. In the illustration given switch 43 is open while switch 47 is closed and its lower terminals are connected with distant station No. 32.

Similar connections are made to the non-private stations, here shown as those stations selected by push buttons 20, 21 and 22. The non-private common leads are designated 100 and 101 respectively. The lead 100 is connected between the movable pole of switch 31 of the talk-listen switch means and a movable pole of the add 20 switch 71. The left contact of switch 31 which is closed in talk position is connected to lead 86 by means of a lead 102. The lead 101 extends between the movable pole of switch 33 of the talk-listen switch means and the other movable pole of the double-pole double-throw switch 71. The lead 101 is connected to the common private lead 85 by means of a lead 103 which extends from the left contact of the switch 33 to the lead 85. Consequently, the voice signal appears across the leads 100 and 101.

The upper contacts of the switch 71 are connected by leads 105 and 106 to the respective movable poles of switch 66 and the lower contacts of switch 71 are connected by means of leads 107 and 108 to the respective movable poles of the switch 68. The upper stationary contacts of switch 66 are connected by leads 110 and 111 to the terminals of a first switch in each group of selector switches connected for non-private conversation, here shown as switches 50, 55 and 60 and the lower stationary contacts of switch 66 are connected by leads 112 and 113 to the terminals of a second switch of each group of selector switches connected for non-private conversation, here shown as switches 51, 56 and 61. It should be noted that the switch 66 is exactly similar to the switch 65 except that switch 66 is in the non-private circuit while switch 65 is in the private circuit. The upper stationary contacts of switch 68 are connected by leads 114 and 115 to a third switch of each group of selector switches connected for non-private conversation, here shown as switches 52, 57 and 62; and the lower stationary contacts of switch 68 are connected by leads 116 and 117 to

a fourth switch of each group of selector switches connected for non-private conversation, here shown as switches 53, 58 and 63. It is thus seen that the switch 68 is similar to the switch 67 except that switch 67 is in the private circuit while switch 68 is in the non-private circuit; and switch 71 is similar to 70 except that switch 70 is in the private circuit and switch 71 is in the non-private circuit.

When the operator of the local station wishes to listen to a distant station he merely connects to the desired distant station by pushing one of the selector buttons 13-22 and if the number of the desired station is above ten, one or both of the "add ten" or "add 20" buttons as above described, and pushes the touch bar 12 to move the switches 30-37 to the position other than that shown in the drawing. This connects the speaker 80 to the output of the amplifier and connects the signal leads (100 and 101) to the input of the amplifier. The speaker lead 81 is connected to the output of the amplifier through the right contact of switch 30, through a lead 120, and through the right contact of switch 35 and the amplifier output lead 79. The speaker lead 83 is connected to the amplifier output through the right contact of switch 32 through a lead 121, and through the right contact of switch 34 and lead 78. A terminal 122 is connected to the lead 120 and a terminal 123 is connected to the lead 121 to provide points of connection for the incoming signal from a master station, inasmuch as this signal has already been amplified at the distant master station and normally need not be amplified further.

However, if the local station is connected to a distant staff station, no amplification of the incoming signal is provided on the distant staff station. The incoming signal from the staff station may be connected to terminals 125 and 126 which are connected to the leads 101 and 100 through the respective switches 36 and 37. Inasmuch as the local station illustrated is a master station it can communicate with any other master station in the system, and therefore, the distant master stations are connected to the local station through the switching system above described. However, a few staff stations may be connected to the master through the terminals 125 and 126 and these staff stations may talk only to the master station to which they are connected. With the talk-listen switch in the position illustrated of course the staff stations connected to terminals 125 and 126 cannot converse with the local master station. However, when the talk-listen switch is thrown to the listen position switches 36 and 37 are closed. Terminal 125 is connected to the amplifier input through switch 36 through a portion of lead 104, through the right contact of switch 33, and through a lead 127 which connects with amplifier input lead 77. Terminal 126 is connected to the amplifier input through the switch 37, a portion of lead 100, the right contact of switch 31, and a lead 128 which connects with amplifier input lead 76. With these connections the signal from the staff station is amplified in the amplifier 75 and is connected to the speaker 80.

The provision of the switching arrangement including the "add ten" push button 23 and its associated switches and the "add 20" push button 24 and its associated switches makes it possible to incorporate any normally desired number of master and staff stations in an intercommunicating

tion system, and the local station with which the switching arrangement above described is associated can communicate with any desired distant master or staff station while utilizing only the twelve push buttons as shown in Fig. 1. If desired, additional contacts can be added to the switches and the number of stations in the system may be increased within practical limits. The cabinet design and construction and the mechanical switching arrangements may be standardized for manufacture on a mass production basis regardless of the fact that the systems may vary in number and arrangements of stations, and the cabinet may be kept small because twelve push buttons will handle any desired number of stations.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. In an intercommunication system wherein a local station may be connected to a plurality of distant stations, a manually operable switching system of the character described for connecting said local station to a selected one of a plurality of distant stations, comprising: manually operable primary switch means mechanically maintained in either of two limiting positions and comprising a number of groups of single-throw switches, each group comprising four of said switches and having a common operating means, each switch having a movable member and a plurality of fixed terminals; manually operable secondary switch means comprising two double-throw switches each having a movable member and a plurality of fixed terminals, said movable members having common operating means; manually operable tertiary switch means comprising one double-throw switch having a movable member and a plurality of fixed terminals; electrical connections

5 between each of said single-throw switches and one of said distant stations; electrical connections between each of said single-throw switches in each group and the fixed terminals of said secondary switch means; electrical connections between the movable members of said secondary switch means and the fixed terminals of said tertiary switch means; and electrical connections between the movable member of said tertiary switch means and said local station.

10 2. In an intercommunication system wherein a local station may be connected to a plurality of distant stations, a manually operable switching system of the character described for connecting said local station to a selected distant station, comprising: manually operable primary switch means mechanically maintained in either of two limiting positions and comprising a number of groups of single-throw switches, each group comprising two of said switches and having a common operating means, each switch having a movable member and a plurality of fixed terminals; manually operable secondary switch means comprising one double-throw switch having a movable member and a plurality of fixed terminals; electrical connections between each of said single-throw switches and one of said distant stations; electrical connections between each of said single-throw switches in each group and the fixed terminals of said secondary switch means; and electrical connections between the movable member of said secondary switch means and said local station.

25 35 ARIE LIBERMAN.
